TRIMMING MATERIAL

Abraham Topiel, New York, N. Y.

Application May 29, 1937, Serial No. 145,423

3 Claims. (Cl. 66—193)

My present invention relates to a Shirred trimming or gathered fabric.

Puckered or gathered strips of cloth are used extensively for trimming upholstery, wearing apparel for women, hats, etc. Heretofore, as far as I am aware, such strips were made puckered on both sides or presented a knotted cord effect on the "back" side, rendering it difficult of attachment. My present invention has as its object the provision of a puckered cloth or trimming which shall have (1) a relatively smooth back surface enabling easy and snug attachment to the article or material to be trimmed, and (2) an especially attractive puckered or gathered "upper" or front side.

Briefly, in carrying into effect my present invention, a series of cords are sandwiched between two strips of cloth. These strips and the cords are run through a knitting machine in such a way, as will be explained in greater detail later, as to produce a trimming or fabric in which one side is shirred or gathered and the other is essentially smooth, especially suitable as a base or attaching surface. Attention is directed to the fact that the "sandwich" should be knitted, for if it is run through an ordinary sewing machine both sides will be puckered or both sides will be smooth.

In the accompanying drawing, which is typical of my invention, Figure 1 is a perspective front view of trimming made in accordance with my invention and illustrates the front puckered, shirred or gathered surface of my trimming or fabric, Figure 2 is a rear elevational view thereof, and Figure 3 is a side diagrammatic view of knitting apparatus for manufacturing my improved fabric.

Referring in detail to the drawing, section K of Figure 1 illustrates my composite fabric or trimming material after the component parts thereof have been knitted together. The section above "K" illustrates the component parts as they are fed to the knitting machine. Specifically, the front surface cloth 2, having the edges 4, 6 folded over, is knitted to the rear cloth surface 8 having similar folded over edges 10, 12. As shown, the cloth strips 2 and 8 are knitted together over the cords 14, 16, 18, 20, 22, 24, and 26. After knitting the surface 2 presents a pleated, ruffled, gathered or puckered front surface as shown in section K, Figure 1, and an essentially or substantially smooth rear, back or bottom attaching surface as shown in Figure 2.

In Figure 3, I have diagrammatically illustrated a side view of apparatus and the way in

which my improved trimming is made. The folded strip 2, 4, 6 of Figure 1 is guided through a suitable flattened guiding cylinder 30 over a fixed guide 32. Similarly, the parallel cords 14 to 26 inclusive, or any suitable filling material, 5 is fed vertically over the fixed guide or stop or abutment 32. A separate cylindrical guide 35 for each of the cords may be provided if desired. The folded backing strip 8, 10, 12 is also fed over the abutment 32 through a suitable flattened cylindrical guide 34.

A bank of eight knitting needles is diagrammatically illustrated in side view at 36 and the thread, which is knitted through the front and back of the strip, is diagrammatically illustrated at 38. Suitable rollers for the strips and cords and suitable weights for tensioning the same may be provided, as found desirable.

As the needles 36 pass through the material, the side of the material nearest the thread 38 20 appears puckered, whereas the other strip 8, 10, 12 is smooth or continuous, as shown in Figure 2. In short, the front of the stitch has the shirr and the back a smooth face. The pleating or shirr may be varied by varying the tension on 25 the cloth by varying the distance between the guiding tubes or cylinders 30, 34 and the abutment 32 or by varying the angle between the flattened cylinders 30, 34. The greater the angle 30 the greater the pleating, etc. I have used successfully for the manufacture of this material a so-called Ruf machine in which the speed of the rollers feeding and drawing the strips and cords through the apparatus controls the length of 35 the stitches.

Although I am not fully certain why the shirr appears on one side and not upon the other, it is my belief that as the needles 36 pass through the strip 2, 4, 6, the strip is moved back on itself slightly in the general direction of guide 30 and 40 then as the needle is pulled through again the cloth does not have time to straighten out before the stitches are completed.

Obviously, the strips may be made of any width and any number of cords may be employed, as found desirable. The strips 2, 4, 6 and 8, 10, 12 may be made of any suitable material such as cotton or crepe acetate. The cords may be of cotton or they may be replaced by cotton filling. The front and back strips 2, 4, 6 50 and 8, 10, 12 may be of the same material or different materials.

Having thus described my invention, what I claim is:

1. A trimming or the like comprising a series 55

- of parallel cords, and a pair of cloth strips attached to said cords, one of said strips being essentially puckered and the other essentially smooth.
- 5 2. A trimming or the like having a shirred front surface and a smooth rear surface, comprising a series of cords and a pair of cloth strips knitted together over said cords.

3. A composite strip comprising two strips of cloth whose edges are folded inwardly and whose inwardly folded edges face one another, a series of parallel cords or filling material between said strips, said strips being knitted together, the knitting being effected at the edges of the strip and intermediate the parallel cords.

ABRAHAM TOPIEL.
